US0D1094172S

(12) **United States Design Patent** (10) **Patent No.:** **US D1,094,172 S**
(45) **Date of Patent:** **** Sep. 23, 2025**

(54) **PLANTER**

(71) Applicant: **Vitra AG**, Birsfelden (CH)

(72) Inventor: **Goupil Thélonious**, Saint-Pierre-en Port (FR)

(73) Assignee: **Vitra AG**, Birsfelden (CH)

(**) Term: **15 Years**

(21) Appl. No.: **29/893,022**

(22) Filed: **May 24, 2023**

Related U.S. Application Data

(63) Continuation of application No. 29/889,347, filed on Apr. 11, 2023, now Pat. No. Des. 1,069,641.
